UNITED STATES PATENT OFFICE.

WILLIAM H. WRIGHT, OF BUFFALO, NEW YORK.

DIE FOR ROLLING STEEL BALLS.

SPECIFICATION forming part of Letters Patent No. 439,712, dated November 4, 1890.

Application filed May 27, 1890. Serial No. 353,305. (No model.)

To all whom it may concern:

Be it known that I, WILLIAM H. WRIGHT, a citizen of the United States, residing at Buffalo, in the county of Erie and State of New York, have invented certain new and useful Improvements in Dies for Making Steel Balls, of which the following is a specification.

The object of my invention is to produce a device that will cut up from a bar of steel or other suitable material the exact quantity of metal required for the purpose, and no more, and rapidly form it into a practically perfect and solid ball of a homogeneous or uniform texture in every portion of the material, so that when hardened it forms a ball of uniform compactness and strength, all of which will be fully and clearly hereinafter described and claimed, reference being had to the accompanying drawings, in which—

Figure 1 is a top plan view of a die illustrating my invention. Fig. 2 is a side elevation of the same, showing the method of forming a true elliptical curve for each side of the die. Fig. 3 is a sectional elevation of one of the dies partly finished, showing its proper position on the face-plate of a turning-lathe while turning the groove in its periphery. Fig. 4 is also a sectional elevation of a die, showing its required position on the face-plate of a turning-lathe for forming the elliptical sides of the groove. Fig. 5 is a front elevation of the die. Fig. 6 is a rear elevation, and Fig. 7 is a diagram showing the different positions of the die from the first position when a parallel semicircular longitudinal groove is cut in the face or periphery of the die to its second position, when a practically true ellipse is given to each side of the die.

To form a true ball by rolling the metal between two dies, I have found it to be absolutely necessary that the sides of the dies should be in the form of as true an elliptic curve as it is possible to make it.

In said drawings, 1 represents the die. The numerals 2 designate the elliptic sides of the same.

In Figs. 1 and 2 I have shown this die adapted to set upon a straight or plane surface, and in Figs. 3 and 4 they are shown curved, which is preferable, thereby adapt-

ing them to be secured to the periphery of a circular disk having one die on the disk and a concave or inwardly-curved stationary die, substantially as shown in my Patent No. 400,990, dated April 9, 1889, or it may be used in the form of two outwardly-curved dies adapted to be secured to the peripheries of two disks constructed to be rotated so that the dies will pass each other in opposite directions while the ball is being cut from a bar and formed between them substantially as I have shown in an application for a patent of even date herewith. I therefore do not limit myself to either a straight, inwardly-curved, or an outwardly-curved die.

I construct my improved die as follows: When an outwardly-curved die is to be made, a curved piece of metal (the best quality of steel) is secured in any well-known way to the face-plate 3 of a lathe in the position shown in Fig. 3 and nicely turned up, a semi-circular longitudinal groove 4 being turned in the periphery. The die is now removed and tempered very hard, and then replaced and secured on the face-plate 3, so that the pin 5 will be directly under the center of the die. The die is now tipped slightly, so as to move one end downward and the other up, substantially as shown in Fig. 7, 8 showing the die in its first position and 9 its second position, it being removed just enough so that when turned up in the line of a circle of the same radius as it was when being turned, as shown in Fig. 3, it will cut off a portion similar to that shown in Fig. 4, the dotted lines showing the shape of the die when first put in, and space between the die and the dotted lines showing the amount cut off, thus cutting an amount from the die commencing at nothing at the heel 6 and gradually deepening until it just reaches the bottom of the groove 4 at the point 7. This operation causes the two sides of the die to assume practically the exact form of an ellipse, substantially as shown in Fig. 1—that is, one-half of a perfect ellipse cut through the shortest diameter. The die being tempered very hard cannot in this second operation be turned by an ordinary lathe-tool. It therefore has to be cut by causing the lathe to move it slowly under a

rapidly-turning emery-wheel, the operation being repeated, taking a slight cut off each time until it is complete. The straight die is made in a similar manner, except a planer 5 is used instead of a lathe. Dies of this form act and force together just enough metal and no more than is required to form a perfect ball of the size the dies are limited to, and it is all gradually forced together with just sufficient force to condense the metal equally 10 throughout.

I claim as my invention—

A die for making steel balls, provided with a longitudinal groove having its two cutting-edges in the form of an elliptic curve the 15 plane of which inclines from the top of a semicircular groove at the heel down to or near the bottom of the groove at the point, substantially as described.

WILLIAM H. WRIGHT.
